DISPLAY FORM

Stephen George Allan, Oklahoma City, Okla.

Application March 13, 1935, Serial No. 10,838

5 Claims. (Cl. 223—68)

This invention relates to display forms and more particularly to those employed in displaying coats, shirts and similar garments and has for its principal object to provide a form of this character with an attachment whereby the form may be readily fitted to garments of different size and shape without the use of padding.

Another important object of the invention is to provide a simple, inexpensive and light weight attachment that can be readily applied to an existing form.

In accomplishing these and other objects of the invention, I have provided improved details of structure, the preferred form of which is illustrated in the accompanying drawing wherein:

Fig. 1 is a perspective view of a form equipped with an attachment constructed in accordance with the present invention.

Fig. 2 is a perspective view of the attachment as it appears before being applied on the form.

Fig. 3 is a vertical section through the form and attachment on the line 3—3, Fig. 1.

Fig. 4 is a fragmentary perspective view of the shoulder portion of the form illustrating one of the hinge members for hingedly suspending the attachment on the form.

Fig. 5 is a section on the line 5—5, Fig. 4.

Fig. 6 is a horizontal section through the form and attachment on the line 6—6, Fig. 3.

Fig. 7 is a perspective view of the screw for adjusting and retaining the attachment in relation to the form.

Referring more in detail to the drawing:

1 designates a conventional type form which is usually constructed of paper board or other light material molded or pressed to shape in simulation of a human torso.

The form illustrated includes back and chest portions 2 and 3, shoulders 4 and 5, and a neck portion 6. The lower parts of the back and chest portions 2 and 3 are drawn inwardly and downwardly to simulate a waist 7 and terminate in a slightly outwardly flaring skirt 8. The side portions 9 and 10 of the form are provided at points in line with the arm portions of the shoulders with disks 11 having convex outer faces 12 to extend slightly within the sleeves of a garment applied on the form.

Located horizontally within the hollow interior 50 of the form, slightly above the waist line thereof, is a partition 13 having an opening 14 therein for passing the upper end of a post 15, the post 15 being carried on a supporting base 16. The form is retained in vertically adjusted elevation relatively to the base by means of a stop collar 17

slidable on the post 15 and having a flange portion 18 engaging under the face of the partition 13. The collar 17 is retained in adjusted position by means of a thumb screw 19 that is manipulated through a notch 20 formed in the skirt of the front portion of the form as best illustrated in Figs. 1 and 3.

Forms of the type just described are furnished in sizes substantially proportionate to the garments to be displayed thereon, but owing to the 10 different shapes of the garments and particularly the lower or skirt portions thereof, it is impossible to fill out the garment without the use of padding. Application of the padding is a tedious and exacting task and requires a great deal 15 of time to give the desired set of the garment.

As above pointed out, it is, therefore, the purpose of the present invention to provide a form of this character with an attachment that may be adjusted relatively to the form to fill out a 20 garment thereon as now to be described.

The attachment is best illustrated in Fig. 2 and includes a shell 21 preferably formed of sheet celluloid material pressed to conform to the shape of the back 2, shoulders 4 and 5 and sides 9 and 10 of the form, the corresponding 25 parts of the shell being designated 2', 4', 5', 9' and 10', respectively.

The lower part of the shell conforms in shape to the rear portion of the waist and skirt 8 as at 30 8' and terminates in horizontal alignment with the bottom edge thereof as best illustrated in Fig. 3.

The vertical side edges 22 and 23 of the shell extend in substantial alignment with the vertical center line of the arm disks 11 and across the median line of the shoulders as at 24 and 25, respectively, the upper edge of the shell being cut away as at 26 to conform to the curvature of the neck 6 as shown in Fig. 1. The side edges 35 22 and 23 are cut away in a similar manner as at 27 and 28 so that the shell can fit closely 40 against the periphery of the disks 11 in completely collapsed position.

Fixed to the shoulder edges 24 and 25 of the shell are pairs of flexible straps 29 and 30 having loops 31 extending through slotted eyes 32 of flat hook members 33 adapted to overlie the shoulder portions of the form. The hook members have prongs 35 adapted to be driven into 45 the form to flexibly and hingedly anchor the loops which suspend the shell from the shoulder of the form. The notched portion 26 which fits about the neck 6 of the form is also provided with a 50 similar strap 36 carrying a hooked prong mem- 55

ber 37 that is driven into the back of the neck as best shown in Fig. 3.

It is thus apparent that the shell is attached to the shoulder portion of the form and depends 5 freely therefrom to provide for adjusting the skirt portion of the form to a garment by moving the skirt portion 9' of the shell toward or away from the form until the garment has the proper set.

This is accomplished by means of a screw 38 10 that is threaded in a bracket 39 attached to the inner wall of the form at a point directly opposite the notch 20. The bracket 39 preferably includes a strip 40 shaped to fit the inner contour of the form and which has its ends secured there- 15 to by suitable fastening devices 41 extending through holes in the bracket and through aligning holes in the wall of the form.

The screw 38 engages in a threaded opening 42 20 in the bracket and has its shank end 43 projecting through an opening 44 in the form so that the end thereof engages against the inner face of the shell. The projecting end of the screw has a reduced extension or pilot 45 for mounting a washer 46 which forms an extended 25 bearing surface for the screw. The reduced extension is preferably of greater length than the thickness of the washer so that it projects through an opening 47 provided in the shell 21. The lower end of the shell is thus supported on the screw 30 extension so as to relieve strain upon the shoulder fastening members above described and to prevent lateral shifting movement of the shell relatively to the form.

In order to facilitate operation of the screw, the 35 inner end thereof is provided with a wing shaped head 48 which may be manipulated through the notch 20.

In fitting a garment to a form equipped with an attachment constructed and assembled as de- 40 scribed, the garment is applied over the form and the skirt portion of the garment is filled out by adjusting the screw 38 so as to move the lower portion of the shell until the proper set of the garment is effected.

45 Since the shell extends from one side of the form to the other, the skirt and back portions thereof are smoothly supported across the entire width of the form and, therefore, the necessity of paddings or other fillings is eliminated.

50 From the foregoing, it is apparent that I have provided an attachment of simple and inexpensive construction which may be readily attached to an existing form.

What I claim and desire to secure by Letters 55 Patent is:

1. In combination with a display form for clothing shaped to fit one style of garment and having front and back portions, shoulder portions and a neck portion, an attachment including 60 a shell shaped to correspond to the back portion of the display form and provided centrally of its upper edge with a recess fitting the neck portion of the form, flexible hinges located at opposite sides of the recess of the attachment and

secured to the same and provided with means for securing them to the shoulder portions of the display form, a flexible hinge arranged centrally of the recess of the said attachment and secured to the same and provided with means for securing it to the neck portion of the display form, and means for adjustably moving the shell on said flexible hinges to fill out the back portion of a garment carried by the display form. 5

2. In combination with a clothing display form 10 having back and shoulder portions shaped to fit one style of garment, an attachment for the form including a shell shaped to correspond to the back and shoulder portions of the form, means hingingly attaching the upper edge of the shell 15 to the shoulder portions of the form, and means for adjusting the lower part of the shell to and from the corresponding part of the form to fill out and extend a garment of a style different from that for which the form is designed without the 20 use of padding.

3. In combination with a clothing display form having back, shoulder and side portions shaped to fit one style of garment, an attachment for the form including a shell shaped to correspond to 25 said portions of the form, means for hingingly attaching the upper edge of the shell to the shoulder portions, and means for adjusting the lower part of the shell to and from the corresponding part of the form to fill out and extend a garment of a 30 style different from that for which the form is designed without the use of padding, said shell having side edges extending over the sides of the form when the shell is collapsed against said form.

4. In combination with a clothing display form 35 having a back portion, shoulder portions and a neck portion, an attachment including a shell shaped to correspond to the back portion of the display form and provided centrally of its upper edge with a recess fitting the neck portion of the 40 form, hinging means located at opposite sides of the recess for attachment of the shell to the shoulder portions of the display form, and means for adjustably moving the shell on said hinging means to effect filling out the back portion of a 45 garment having a style different than the one for which the form is shaped without the use of padding.

5. In combination with a display form for clothing to fit one style of garment and having 50 front and back portions, a shoulder portion and a neck portion, an attachment including a shell shaped to correspond to the back portion of the display form and provided centrally of its edge with a recess fitting the neck portion of the form, 55 flexible hinges located at opposite sides of the recess secured to the form and provided with means for securing same to the shoulder portion of the display form, and means for adjustably moving the shell on said flexible hinges to fill out the back portion of a garment having a different 60 style than that for which the form is designed.

STEPHEN GEORGE ALLAN.
